(Cl. D61—1)

To all whom it may concern:

Be it known that I, Nathaniel B. Wales, a citizen of the United States, residing at New York, in the county of New York and State of New York, have invented a new, original, and ornamental Design for a Projection Machine Cabinet, of which the following is a specification, reference being had to the accompanying drawing forming a part thereof, in which

Figure 1 is a front view of a projection machine cabinet showing my new design, the surfaces not shown being plain surfaces.

Figure 2 is a top view.

I claim:

The ornamental design for a projection machine cabinet, as shown and described.

NATHANIEL B. WALES.
